BLAST DOOR SEAL

Malvin G. Jacobson, Coon Rapids, and Palmer G. Wern-
ager, Minneapolis, Minn., assignors, by mesne assign-
ments, to the United States of America as represented
by the Secretary of the Navy

Filed Apr. 27, 1961, Ser. No. 106,422
7 Claims. (Cl. 20—16)

This invention relates generally to closures, and more
particularly it pertains to a seal strip arrangement for
sealing the edges and abutments of doors.

The primary object of this invention is to provide a
leak-proof seal for doors which are exposed to explosive
blast.

Another object of this invention is to provide a seal
strip which automatically adjusts its closure to the out-
side pressure.

Other objects and many of the attendant advantages of
this invention will be readily appreciated as the same
becomes better understood by reference to the following
detailed description when considered in connection with
the accompanying drawings wherein:

FIG. 1 is a rear elevation of a blast door and a portion
of its surrounding frame;

FIG. 2 is a vertical section drawing taken along the
line 2—2 of FIG. 1;

FIG. 3 is a detailed cross section, much enlarged, taken
along line 3—3 of FIG. 1; and

FIG. 4, is a detail cross section similar to FIG. 3 taken
along the line 4—4 of FIG. 1.

In accordance with the invention in one of its aspects,
there is provided a pair of heavy steel blast doors 14 set
into a frame 12 of a sloping deckhouse bulkhead 10, as
shown in FIGS. 1 and 2. These blast doors 14 are
utilized in connection with guided missile launching sys-
tems, for passing missile-booster combinations from the
deckhouse to a launcher which receives and launches the
missile-booster combinations. After the missile-booster
combinations have been passed through the opened blast
doors 14, the doors are then closed and are used to pro-
tect and shield missile-booster combinations and person-
nel in the deckhouse from the liberated exhaust gases
from the booster when a missile-booster combination is
launched into space from the launcher located outside
of the deckhouse.

As shown best in FIGS. 1 and 2, the blast doors 14 are
arranged to be opened on spaced side hinges 16. When the
blast doors 14 are closed they overlap the
frame 12 and join together in abutting relationship as
will be related.

Following the inside faces of the edges of the blast
doors 14 which mate with the door frame 12, a sealing
arrangement designated generally by reference numeral
18, is provided as best shown in FIG. 4. The same seal-
ing arrangement 18 is located at the junction of the blast
doors 14 as illustrated in FIG. 3.

The sealing arrangement 18 consists of structure having
opposing grooves 20 and 28 in the door-to-door juncture
or door-to-frame juncture as the case may be. The
groove 20 contains a sealing strip 22 of resilient material
such as rubber of U-shaped cross-section with an inside
liner strip or spring 24 of metal. The spring 24 in addi-
tion to providing an outwardly expanding force to the
strip 22 also defines in cross-section a J-shaped expansion
chamber 26 therein.

A buffer strip 30 of rubber is secured within the op-
posite groove 28 and it contacts the side of sealing strip
22 when the doors 14 are closed. The strip 22 is posi-
tioned within the groove 20 so that the chamber 26 opens
outwardly with respect to the outside of the door 14
or the uncovered periphery of the frame 12. Contiguous

2

to this open side of the chamber 26, the groove 20 is
flared for a passageway 36 which communicates with the
peripheral door-to-door or door-to-frame interface and
thence to the outside atmosphere.

5 Thus, any fluid leakage through this interface from the
outside such as from the battering of sea waves or the
force of gases from a rocket blast is channeled through
the passageway 36 to the chamber 26 to there expand and
add pressure to the urging of spring 24 against the strips
22 and 30. Consequently, the interface pressure and
seal of sealing strip 22 with strip 30 is proportioned to
the leakage of fluid from the outside which in the case
of rocket blast may reach great magnitude.

The vertical joint or abutment of the doors 14 is pref-
erably baffled with a tongue 32 on one door 14 and a
mating groove 34 on the other door 14 on the blast or
outer side of the sealing arrangement 18 as illus-
trated in FIG. 3.

In lieu of this baffle tongue and groove 32 and 34 the
seals 18 for the door frames 12 are preferably provided
with a supplemental expansion chamber 38. As shown
in FIG. 4, this chamber 38 is on the exterior side of
the seal 18 and is cut partly in the door 14 and partly
in the frame 12. The supplemental expansion chamber
38 functions by absorbing and peripherally distributing
localized pressure peaks from the blast gasses uniformly
to the seal 18.

Obviously many modifications and variations of the
present invention are possible in the light of the above
teachings. It is therefore to be understood that within
the scope of the appended claims the invention may be
practiced otherwise than as specifically described.

What is claimed is:

35 1. A door seal for sealing the crack between a door
and a door frame comprising a door and a frame meet-
ing in face to face relationship, a first groove along the
edges of the frame that contacts said door, a first strip
of resilient material placed in said first groove, a sub-
stantially U-shaped channel cut longitudinally along the
resilient material, a second groove along the edge of the
door opposite said first groove in said frame, and a
second strip of resilient material placed in the second
groove and contacting said first strip whereby any leakage
between the door and the frame spreads the U-shaped
45 channel to increase the contact between the two resilient
strips.

2. A door seal as set forth in claim 1 and further com-
prising a U-shaped spring positioned within the U-shaped
channel, said spring spreading said channel to force said
50 first strip into sealing engagement with said second strip.

3. A door seal for sealing the crack between a door
and a door frame comprising a door and a frame meet-
ing in face to face relationship, a first groove along the edges
55 of the frame that contacts said door, a first strip of resil-
ient material placed in the groove, a substantially U-
shaped channel cut longitudinally along the resilient ma-
terial, a narrow passage joining the U-shaped channel
and the crack between the door and frame, a second
groove along the edge of the door opposite said first
60 groove in said frame, and a second strip of resilient ma-
terial placed in the second groove whereby any leakage
between the door and the frame moves along the narrow
passage into the U-shaped channel spreading the channel
to increase the contact between the resilient strips.

4. The seal of claim 3 further comprising a spring
70 positioned in the channel to aid in spreading the chan-
nel to force said first strip into sealing engagement with
said second strip.

5. A door seal as described in claim 4 wherein there
is further provided a supplemental expansion chamber
cut into the door and the frame transverse to the crack

between said door and frame, said chamber positioned between extremities of the crack.

6. A door seal for sealing the crack between the abutting edges of a first and second door comprising a first groove along the abutting edge of the first door, a first strip of resilient material located within said first groove, a slightly larger second groove along the abutting edge of the second door opposite said first groove, a second strip of resilient material in the second groove so that it will contact the resilient material in the first groove when the two doors are in abutting relationship, a larger wedge-shaped groove along the edge of the first door, a wedge-shaped tongue along the edge of the second door to mate with the wedge-shaped groove when the doors are in abutting relationship, a substantially U-shaped channel extending longitudinally along the center of the resilient material in the second door, and a narrow passage joining the U-shaped channel and the wedge-shaped groove, said U-shaped channel having its open end opening in a direction parallel to the crack between the doors, so that fluid leakage is modulated by the wedge-

shaped tongue and groove and enters said U-shaped channel to spread said U-shaped channel forcing said strips into sealing engagement.

7. A door seal as described in claim 6 wherein there is further provided a spring positioned within the U-shaped channel to aid in spreading the channel to force said second strip into sealing engagement with said first strip.
